(57) **CLAIM**

We claim the ornamental design for a control knob for cooking appliances with animated icon, as shown and described.

DESCRIPTION

FIG. 1 is a front elevation view of a control knob for cooking appliances with animated icon, showing a first image in a sequence thereof, according to a first embodiment;

FIG. 2 is a front elevation view of the control knob for cooking appliances with animated icon, showing a second image in a sequence thereof;

FIG. 3 is a side elevation view thereof;

FIG. 4 is a front elevation view of a control knob for cooking appliances with animated icon, showing a first image in a sequence thereof, according to a second embodiment;

FIG. 5 is a front elevation view of the control knob for cooking appliances with animated icon, showing a second image in a sequence thereof; and,

FIG. 6 is a side elevation view thereof.

The appearance of the transitional image sequentially transitions between the images shown in FIGS. 1-2 and FIGS. 4-5 respectively. The process or period in which one image transitions to another image forms no part of the claimed design.

The broken line immediately adjacent the shaded edge surface in FIGS. 3 and 6, respectively, illustrates the boundary of the claimed design and forms no part thereof. The remaining broken lines in FIGS. 1-2 and 4-5, respectively, illustrate portions of the control knob and portions of the icon which form no part of the claimed design. The outermost solid circular line depicts the control knob and all solid and broken lines therein depict portions of the icon.
